UNITED STATES PATENT OFFICE.

WILLIAM J. BODA, OF DAYTON, OHIO.

HINGE.

SPECIFICATION forming part of Letters Patent No. 407,809, dated July 30, 1889.

Application filed April 16, 1889. Serial No. 307,395. (No model.)

To all whom it may concern:

Be it known that I, WILLIAM J. BODA, a citizen of the United States, residing at Dayton, in the county of Montgomery and State 5 of Ohio, have invented certain new and useful Improvements in Hinges, of which the following is a full, clear, and exact description, reference being had to the accompanying drawings, forming part of this specification.

10 My invention relates to an improvement in hinges for adjusting doors, and has for its object the improved construction of such hinges.

The novelty of my invention will be here- 15 with set forth, and specifically pointed out in the claims.

In the accompanying drawings, Figure 1 is a sectional plan through the rear or hinging end of a door, its jamb, and facing, showing 20 the application of my improved hinge. Fig. 2 is a sectional elevation through the dotted line $x-x$ of Fig. 1, looking in the direction of the arrow. Fig. 3 is an elevation of the half of the hinge which is secured to the door. Fig. 4 is an elevation of the half of the hinge which is secured to the jamb. Fig. 5 is an elevation of a portion of the rear edge of the door, showing the covering-plate. Fig. 6 is a 25 detail plan view of one of the fastening-lugs. The same letters of reference are used to indicate identical parts in all the figures.

A represents the rear or hinging side of a door, B the jamb to which it is hinged, and C the facing, extended in this instance beyond the jamb to afford a bearing for that 30 part of the hinge which is secured to the jamb. The part of the hinge secured to the jamb consists of a flat back plate a , a right-angular flat plate b , bearing against the rear side of the facing, and a projecting plate c in a plane parallel with the plate a and provided with a central knuckle d . The rear side of the plate a has two or more, in this instance two, threaded or barbed lugs e , having 35 tapering splits, as seen at f , Fig. 6, with the enlarged part of the split next to the plate, and having small circular openings g through the plate into said splits, as seen in Fig. 4. These lugs e are fitted into bores in 40 the jamb, and pins h are driven through the openings g and, as the metal is usually

wrought or malleable, serve to spread the lugs, as seen in Fig. 1, thereby effectually locking the plate a to the jamb. Ordinary screws i may be employed for securing the 55 plate b to the facing.

The outer half of the hinge upon which the door is secured and adjusted consists of a flat face-plate j in line with the plate b , and a right-angular portion k , lying upon the 60 plate c and having end knuckles l , between which the knuckle d fits and is hinged by the usual pintle m . Upon the inner face of the plate j there are three projecting lugs n, n , and o . The outer ones n, n have eyes p at 65 their extremities, and, as seen in Fig. 1, I prefer to make them in two parts screwed together to obtain adjustment for the eyes. The central lug o is flat and has a slot q in its rear edge.

The face of the door has recesses r , Fig. 2, cut into it to receive the lugs n, n, o , and these recesses are sufficiently large to allow for the adjustment of the door, though they are at all times covered and concealed by the plate j . 70 The rear edge of the door has horizontal bores s, s, t , Fig. 2, opening into and through the recesses r and coincident with the lugs n, n , and o , respectively. A screw u with an annular slot v is fitted into the bore t , and the 75 slotted end of the lug o fits in this slot v . Taper-screws w are inserted in the bores s, s and pass through the eyes p , whose inner bores are made sharp, as seen at y , Figs. 1 and 80 3, to fit the threads of the screws w .

85 From this construction it will be seen that by first loosening the screws w and then turning the screw u the door may be adjusted so as to hang true and not bind, and, when so adjusted, by screwing up the taper-screws w 90 the plate j is firmly clamped to the door. For neatness of finish it is desirable to cover the bores s, s, t with a covering-plate D, Figs. 1 and 5, which is held in place by wood-screws z . This plate of course has to be removed 95 whenever it is desired to adjust the door.

The purpose of making the eyes p adjustable is to enable them to suit any untrue boring of the bores s, s , as will be readily understood.

Having thus fully described my invention, I claim—

1. A hinge having the leaf which fits upon the door provided with inwardly-extending lugs having eyes and adapted to fit in recesses in the door and be clamped by tapering screws inserted in the rear edge of the door, substantially as described.
- 5 2. A hinge having the leaf which fits upon the door provided with inwardly-extending lugs, to which adjustable eyes are secured and adapted to fit in recesses in the door and

be clamped by tapering screws inserted in the rear edge of the door, substantially as described.

15 3. A threaded or barbed fastening-lug for hinges, split up to the plate from which it projects, and having an opening from said split through the plate for the insertion of a pin to spread the lug, substantially as described.

20 WILLIAM J. BODA.
